STEMMER FOR TOBACCO LEAVES

George W. Gwinn, Hewlett, N. Y., and James W. Leary, Bloomfield, N. J., assignors to International Cigar Machinery Company, a corporation of New Jersey

Application September 5, 1936, Serial No. 99,574

22 Claims. (Cl. 131—123)

This invention relates to tobacco handling machines, and more particularly to machines for stemming tobacco leaves preparatory to the fabrication of the tobacco into cigars, cigarettes and other tobacco products.

The present invention relates to a stemming device operating on the general principle of and constitutes improvements on the machine disclosed in co-pending application Ser. No. 48,353, filed in the United States Patent Office November 5, 1935, by Wilhelm B. Bronander, and which has matured into Patent No. 2,165,217 dated July 11, 1939. However, the structure of the present invention embraces additional features for operating upon a leaf prior to the stemming operation which greatly increases its practicality and efficiency.

In stemming tobacco, one of the chief problems is to completely remove from the stems all of the web portions or laminae of each leaf, and thereby eliminate any waste of the web portion. The great variations in leaf structure in tobacco, especially in the several varieties of tobacco, the fact that leaves may become torn during curing 25 and packing, and the non-uniformity of stems of individual leaves, add greatly to the necessity of producing a machine which will overcome all of these many defects, and handle and stem each leaf as if it were one of a homogeneous group. It is, therefore, the chief object of this invention 30 to provide a machine which will more effectively stem tobacco than has been possible heretofore.

It is a further object to provide spaced cutting elements so formed and positioned that they will yieldingly press against and follow the stem 35 of a leaf being progressed past their cutting edges, and remove therefrom substantially all of the laminae thereof without cutting into said stem.

Another object is to properly position and spread leaves and then maintain them under a constant tension as they are fed to the stemming mechanism. This treatment will tend to straighten out twisted leaves to a greater extent 40 than heretofore and also to present straighter stems to the stemming mechanism.

The invention also consists in means for resiliently supporting the cutting members so that they can be positioned on inclined axes to operate 45 on and stem tobacco leaves.

The invention also contemplates the provision of means for separating the biased cutting members either manually or automatically so that the ends of stems may be readily introduced between 50 said members for proper stemming.

A further object of the invention is to provide mechanism for properly preparing leaves for stemming by positioning and spreading the web portions thereof prior to the introduction of their stems between the cutting members.

An additional object of the invention is the provision of a suction support for leaves, and a pneumatic spreading device located above the support for spreading the laminae of leaves positioned on said support. The invention also 10 contemplates the use of either stationary or movable spreading devices. A further object of the invention is to provide novel means for severing laminae from the stems of leaves and includes a flexible, disk cutting member which may be 15 dished or flanged on its periphery. The cutting edge may have serrations formed thereon.

An added object is to provide a continuous stemming machine having means for continuously feeding leaves to stemming members and means 20 for positioning said members so as not to interfere with the approaching feeding means.

A further object is to furnish rotary resilient disk cutting members rotating on inclined axes for cutting laminae of leaves from their stems, 25 and a device for supporting the tips of leaves against said cutting members.

An additional object is to provide flexible cutting members rotating on inclined axes for cutting laminae from stems of leaves, auxiliary supporting means comprising a rotary device located adjacent said members and guide means for directing the laminae away from said members.

A further object is to provide a novel support for leaves to be stemmed in which said support 35 is provided with a central suction portion for holding leaves in position, and downwardly inclined sides upon which the web portions thereof may be spread. The invention also includes an extended leaf guide plate positioned adjacent the 40 support over which leaves are fed to the stemming knives.

With these and other objects not specifically mentioned in view, the invention consists of the novel construction and combinations set forth 45 herebelow in the specification and disclosed in the drawings and in the claims hereunto appended.

In the accompanying drawings:

Fig. 1 is a plan view of the improved stemming 50 machine for tobacco leaves;

Fig. 2 is a side elevation of the same;

Fig. 3 is a plan view showing the flexible stemming element in detail;

Fig. 4 is a partial sectional end elevation of the 55

improved stemming machine, taken on line 4—4 of Fig. 1;

Fig. 5 is a sectional side elevation of a leaf-tip guiding and cutting device taken on line 5—5 of Fig. 6;

Fig. 6 is a plan view of the same;

Fig. 7 is a side elevation of the improved stemming machine in a modified form equipped with an automatic leaf carrying device; Fig. 7a is a fragmentary detail view in vertical section, taken on the line 7a—7a of Fig. 7; and

Fig. 8 is an end elevation of the same taken on line 8—8 of Fig. 7.

The improved tobacco leaf stemming machine consists of a table 10 having mounted thereon a leaf support 11 provided with a perforated center portion or plate 12, and sides inclining downwardly from plate 12 towards table 10, thereby providing means for easily positioning and spreading leaves. Beneath plate 12 is mounted a suction box which, by means of a funnel 14 and a pipe 15, is connected to the suction inlet of a fan 16 supported by a shelf 17 of the table 10. Perforated suction plate 12 also acts to firmly hold spread leaves as they are being stemmed, and furnishes a resistance against too rapid pulling through the stemming members. Because of the relatively constant tension in a given leaf stem while being progressed through the stemmers, the tendency is for crooked stems to straighten out. Fan 16 is driven by a pulley 18 and a belt 19 running over a pulley 20 mounted on shaft 21 of a motor 22 also supported by and fastened to said shelf 17. The leaf support 11 is also equipped with a horizontally extended leaf guide plate 23 over which the leaf to be stemmed is fed into the flexible stemming element, the plate 23 being provided at its rear edges with wings 23a which slope downwardly along the sides of the support 11. The stemming element consists of a pair of angularly arranged flexible rotating, cutting disks 24 which may be formed of thin, spring steel or the like, each of which is mounted on a horizontal shaft 25. The shafts 25 are rotatably supported in horizontal sleeves 26, held by lugs 27 mounted on vertical shafts 28 supported in bearings 10a of table 10. On the lower portion of each shaft 28 is fixed an arm 29, which arms are connected together by a link 30. To one of the arms 29 is pivoted a connecting rod 31 which is attached to one arm of a bell crank lever 32 pivoted to a stud 33 held by a bearing bracket 34 mounted on table 10 so that when the lever 32 is moved disks 24 will likewise be moved to and from each other to allow stem ends to be brought between them for stemming purposes. The other arm of bell crank lever 32 is connected by a link 35 to a foot pedal 36 pivoted to a supporting bracket 37. The peripheral portion of each knife disk 24 is either dished or formed with a curve or flange 38, the outer edge of which is provided with serrations 39. By means of this arrangement, the flange portion 38 of disk 24 will allow the stems 65 to be easily inserted between the flexible blades and when the knives are brought together there will be little danger of their cutting into the stem sides. These blades, therefore, follow any curve or size of stem without danger of the serrations 39 cutting into the same while separating the stem S from the leaf L which is pulled through said knife disks 24 by an operator or mechanical means. Disks 24 are driven by means of their respective shafts 25, each of which carries a pulley 40 operated through a belt 41 and a pulley 42

from a shaft 43 supported in bearing brackets 44 (Fig. 2) fastened to shelf 17. Shaft 43 is driven through a conventional pulley 48 (Fig. 8) and a belt 45 (Fig. 2) from a pulley 46 mounted on motor shaft 21.

In order to assure that the leaf being stemmed is well open and flat while being pulled through the stemming mechanism, the stemming machine is provided with a leaf spreading device. The latter consists of a blower box 47, the bottom of which is formed by a stem guide bar 48 provided with slots 49 and holes 50 (Fig. 3) directing an air blast supplied to the blower box 47 towards the center portion of the leaf L. In order to obtain an efficient spreading effect upon the leaf L, the air blast is then directed from the center portion of the leaf to the outer edge of the same by means of a baffle plate 51 attached to the lower portion of blower box 47, this baffle plate structure, as illustrated, preferably being formed with a substantially planar lower surface, to confine the blast substantially to the path of the leaf while permitting the blast to flow laterally. The air blast is supplied by means of fan 16 and conducted from the blower outlet 52 of the same through a flexible hose 53 into a pipe 54 attached to the top portion of the blower box 47. For the purpose of facilitating the raising and lowering of the leaf spreading device just described, the pipe 54 of said blower box is provided with a collar 55 carrying a stud 56 (Figs. 1 and 2) loosely engaging with and thereby pivotally supported from an arm 57 mounted on a shaft 58 supported by means of a bearing bracket 59 attached to table 10. Arm 57 is provided with a lug 57a cooperating with an adjusting screw 57b mounted in table 10 so that the position of box 47 may be readily adjusted to that desired. The shaft 58 furthermore carries a hand and operating lever 60.

In operating the improved stemming machine, the operator first presses hand lever 60 in a downward direction, which causes the lifting of the spreading device. The leaf L to be stemmed is then placed upon the leaf support 11 and held to the latter by means of the suction supplied through the perforated center plate 12. The operator then lowers the spreading device again, depresses foot pedal 36, and, through link 35 and bell crank lever 32, causes the knife disks 24 to swing away from the center of the machine. The operator then adjusts the position of the leaf in such a manner that the butt end of the stem partly extends from the guide plate 23 and, upon releasing foot pedal 36, the curved portions 38 (see Fig. 3) may contact the sides of said stem as the disks come together again. A tension spring 61 pivoted to bell crank lever 32 and anchored to table 10 normally urges the spaced knife disks 24 as close together as possible, thus effecting a steady yielding contact of the flange portion 38 with the stem S which is pulled by the operator through said stemming elements. The importance of the flange on the flexible cutting members is at once evident when it is pointed out that it lets each blade hug each stem closely and, therefore, accomplish extremely close stripping. This also makes it possible to strip with equal success any type of leaf regardless of whether the stems thereof are straight or crooked, since the flexible blades adapt themselves readily to the contours of all stems. While the stem, during stemming operations, is held by the operator, the two half leaf portions cut from said stem fall onto a chute plate 62 held by means 75

of guide plate 23 and table 10. In order to prevent injury to the operator, a pair of stationary, shielding plates 62, mounted on sleeves 26, are provided. The portion of the plate 62 below the knives 24 and shields 63 is depressed to admit the same and permit rotation thereof. A stop screw 64 adjustably held by means of lug 65 on table 10 is installed for the purpose of preventing the rotating knife disks 24 from contacting each other after leaf and stem are pulled away from said stemming element, and also locates the cutting members in proper stemming relation. It is to be noted that spring 61 also functions to hold the members 26 yieldingly against the stop 64.

15 As the tip end of the stem is often very thin and therefore offers no guidance or resistance to the rotating knife disks 24, the latter have the tendency to throw the tip end of the leaf downward without cutting the same. This action may easily be prevented by means of an additional tip end guide and support mechanism illustrated in Figs. 5 and 6. Said guide and support mechanism consists of a thin rotating disk 66 flanked by two thin guide plates 67, all of which are mounted between the two rotating disks 24 at the edge of the guide plate 23. Disk 66 is mounted on a shaft 68 driven by means of a pulley 69 and a belt 70 from another conventional pulley (not shown) on shaft 43. Shaft 68 is supported by suitable bearing brackets 71 (Fig. 5) attached to the lower side of guide plate 23 on which also the two thin guide plates 67 are mounted.

As illustrated in Figs. 7 and 8, the improved tobacco leaf stemming machine may also be operated in conjunction with an automatic leaf carrying device. The latter consists of a pair of spaced, continuously moving, endless conveyor chains 72 which are supported over the entire length of the machine upon a pair of driving sprockets 73 and a pair of idler sprockets 74 (Fig. 7). The latter are fixed to a shaft 75 loosely supported in bearings in brackets 76 attached to table 10. Driving sprockets 73 are keyed to a shaft 77 loosely supported in bearings in brackets 78 which are fastened to the delivery end of table 10. Shaft 77 is driven by means of a sprocket 79 (Fig. 8) actuated through a chain 80 by a sprocket 81 (Fig. 7) mounted on a shaft 82 extending from a reduction gear box 83 suitably positioned beneath table shelf 17 (Fig. 7). Gear box 83 is actuated by means of a shaft 84 carrying a sprocket 85 which, through a chain 86, is driven by a sprocket 87 (Fig. 8) mounted on shaft 43. The latter is driven through a pulley 88 and belts 45 from pulley 46 mounted on motor shaft 21 of motor 22. The two parallel mounted conveyor chains 72 are connected to each other by means of a number of properly spaced horizontal bars 89, each having pivoted thereon grippers comprising a pair of gripper fingers 90 provided with operating lugs 91 and a pivoted roller 92 on each lug. The pairs of grippers 90 are normally held closed by means of a compression spring 93 (Fig. 8). In order to open said gripper fingers for the purpose of inserting the butt end of the stem S between them at the feed end of the machine, a pair of cam bars 94 are placed in the path of rollers 92 which, upon making contact with said bars, will cause the opening of said gripper fingers and the butt end of a stem S of a tobacco leaf is placed between said open fingers by the operator. As soon as rollers 92 disengage from bars 94, the spring 93 between said fingers will cause the closing of the same, thereby gripping the butt end of said stem firmly and drag-

ging the leaf L to be stemmed over the leaf support 11 beneath the spreading device which spreads the leaf, and through the flexible stemming means described previously. Bars 94 are attached to brackets 76. After the stemming operation is completed, the gripper fingers are automatically opened again at the delivery end of the machine and the stem S may be dropped in a suitable container (not shown). The opening of said gripper fingers at the delivery end of the machine is accomplished in a similar fashion as at the feed end of the same. Rollers 92 for a short period, engage again with a pair of stationary cams 95, thus causing the fingers 90 to open and allowing the stem S to slip out and drop into a desired container. Of course, as soon as rollers 92 disengage from cams 95, said gripper fingers will automatically close again and remain closed until they arrive at the feed end of the machine for a new cycle. Conveyor chains 72 carrying said gripper fingers 90, travel continuously in the direction indicated by the arrows in Fig. 7. Cams 95 are stationarily held by means of a supporting bar 96 attached to brackets 76.

In order to prevent interference between the rotating cutting discs 24 and the continuously traveling gripper fingers 90, said cutting discs are swung away from each other and the center of the machine and out of the path of said gripper fingers upon approach of the same. As soon as said fingers have passed said discs, the latter immediately return and upon engaging with the stem S, commence their cutting action in the same manner as described heretofore, except that the leaf is steadily advanced by said gripper fingers 90 and chains 72 instead of being pulled by the operator.

The automatic withdrawal of cutting discs 24, as a traveling gripper approaches, is achieved by means of a rotating cam 97 engaging with a roller 98 pivoted to a cam lever 99 mounted on shaft 33a supported by a bearing bracket 34a. To shaft 33a is furthermore fastened a lever 100 to which is pivoted the connecting rod 31 operating, through arms 29, link 30 and vertical shafts 28, the knife shaft supporting lugs 27 acting in the same manner as achieved by operating the foot pedal 36 and manually separating the knives. In order to assure a steady contact of roller 98 with cam 97, a tension spring 61a is provided. Cam 97 is mounted on a shaft 101 supported in bearing bracket 78. Shaft 101 is driven in proper timed relation with conveyor drive shaft 77 by means of a sprocket 102 and a chain 103 engaging with a sprocket 204. The latter is fastened to shaft 77 while sprocket 102 is mounted on shaft 101.

In this modified machine, the knife driving means as well as the leaf supporting arrangement are of identically the same construction as in the first embodiment of the invention described, the leaf support 11 being supplied with suction from the fan 16 in the same manner as described in that construction. In order to accommodate the passing gripper fingers 90, the blower box of the leaf spreading device in this modification is divided into two halves 104 (Fig. 7 and Fig. 7a) which, in this case, are stationarily fixed in proper position above support 11 by means of arms 105 attached to table 10. Each half 104 of the blower box is connected to the blower outlet 52 of fan 16 by means of a pipe 106 (Fig. 7).

The various means and parts may be widely varied in construction within the scope of the claims for the particular device selected to illus-

trate the invention is but one of many possible concrete embodiments of the same. The invention, therefore, is not to be restricted to the specific construction shown and described.

5. What is claimed is:

1. In a tobacco stemming machine, the combination with a pair of flexible cutting disks arranged to receive the stem of a tobacco leaf between them and cut the laminae therefrom as said leaf is moved past them, driving means for rotating said cutting disks to impart cutting movement to said disks, and a suction guide table upon which said leaf is spread and moved to said disks, said table having associated therewith means to support said disks with a yielding bias firmly toward contacting relation of the proximate faces of said disks with a stem inserted therebetween, while permitting free flexure of the cutting edges of said disks to a position for severing the leaf portions progressively along their regions immediately adjoining the tapering stem, without cutting into said stem.

2. In a tobacco stemming machine, the combination with a pair of spaced cutting disks having their axes inclined towards each other, arranged to receive the stem of a tobacco leaf between them and cut the laminae therefrom as said leaf is progressed past their cutting edges, driving means for rotating said disks to impart thereto cutting movement, and a table upon which leaves are spread prior to their insertion between said disks.

3. In a tobacco leaf stemming machine, the combination with a pair of rotary, flexible stemming disks having serrated cutting edges spaced to receive the stem of a leaf between them to shear the blade portions therefrom, driving means for imparting severing motion to said disks whereby the edges thereof sever the blade portions from the stem and a guide table upon which said leaves are spread out and positioned as they are inducted between said disks, said table having associated therewith means to support said disks with a yielding bias firmly toward contiguous relation of the proximate faces of said disks with a stem inserted therebetween, while permitting free flexure of the cutting edges of said disks to a position for severing the leaf portions progressively along their regions immediately adjoining the tapering stem, without cutting into said stem.

4. In a tobacco leaf stemming machine, a suction leaf spreading table upon which a leaf to be stemmed is positioned and spread, a pair of flexible spaced, rotary, flanged cutting disks located adjacent said table and between which the stem of said leaf is moved, and by which the leaf blade portions are removed from the stem.

5. In a tobacco leaf stemming machine, a suction leaf positioning table upon which leaves to be stemmed are located, flexible resilient rotary cutting disks provided with curved cutting edges located adjacent said table and cooperating therewith, said disks being so constructed and arranged that when leaves are fed with the stem of each leaf passing between said disks the curved cutting edges yieldingly follow the stems by virtue of the inherent flexibility and resilience of the disks, and sever the laminae thereupon.

70. 6. In a tobacco leaf stemming machine, a leaf positioning support, a pair of spaced flexible disks having cutting edges for closely following and separating the stems of leaves from the laminae thereof, means for rotating said disks whereby leaves passed between them have their

laminae cut from said stems by said edges, said cutting edges being inclined relatively to the broad faces of said disks to promote lateral flexure and avoid cutting into the stems.

7. A tobacco leaf stemming device comprising a leaf spreading table, a pair of spaced flexible stemming members located adjacent said table, and means for forcing a blast under pressure divergently against the upper surface of a leaf positioned upon said table to spread the same prior to the movement of said leaf between said members.

8. A tobacco leaf stemming device comprising a pneumatic leaf spreading table, a pair of spaced flexible stemming members located adjacent said table, and means for forcing a gaseous fluid upon a leaf positioned upon said table to spread the same prior to the stemming operation, said means including a blower box, and means for raising and lowering said box into operative position with respect to leaves on said table.

9. In a tobacco leaf stemming machine, the combination with a pair of spaced flexible cutting members biased to form a V-shaped cutting opening, of a leaf positioning table adjacent said members, and means for imparting cutting movement to said members whereby web portions of leaves are cut from the stems as said leaf is moved between said members, said members being provided with flanged cutting edges directed away from the stem being passed between said members to prevent said edges from cutting said stem.

10. In a tobacco stemming machine, the combination with a pair of spaced stemming members comprising flexible rotary cutting disks mounted on inclined axes, of a feed support for leaves, means for rotating said disks to impart cutting movement thereto, and means for mounting said disks for yielding movement to and from each other.

11. In a stemming mechanism for tobacco stemming machines, a plurality of rotary flexible stemming members for cutting the stems from leaves fed therebetween, guide means over which leaves are fed to said members, and auxiliary guides positioned closely adjacent said members for supporting each leaf tip portion against said members as it moves therebetween, said auxiliary guides being so disposed as to permit free lateral flexure of the cutting edges of said flexible rotary members to the extent induced by the contact of the cutting edges with the broad end of the stem.

12. In a stemming mechanism for tobacco stemming machines, a plurality of rotary flexible stemming members for cutting the stems from leaves fed therebetween, and support means for unstemmed parts of said leaves positioned closely adjacent said members for supporting said portions, said means comprising a pair of spaced guide plates and a rotatable disk cooperating therewith.

13. A cutting member for a tobacco stemming machine comprising a rotary flexible disk, said disk having a flanged cutting edge which bears resiliently against the stem of a leaf being stemmed, said flange being outwardly curved away from said stem to prevent cutting into said stem.

14. A cutting member for a tobacco stemming machine comprising a rotary flexible disk provided with a flanged cutting edge, said edge having thereon a plurality of serrations.

75. 15. A cutting member for a tobacco stemming

machine comprising a rotary flexible disk provided with a curved cutting edge having thereon a plurality of serrations, and a guard member of greater width than the radius of said disk 5 cooperating with said disk to prevent an operator from contacting the cutting edge of said disk, said guard member being so disposed as to permit free lateral flexure of the cutting edge of said rotary flexible disk to the extent induced 10 by the contact of the cutting edge with the broad end of the stem.

16. In a tobacco leaf stemming machine, a table over which leaves are spread and fed, a pneumatic leaf spreading device located above 15 said table adapted to direct air under pressure divergently against the upper surface of leaves to be spread, a pair of pivotally mounted flexible cutting members mounted adjacent said table for receiving leaves fed from said table, and 20 means for imparting cutting movement to said members whereby the web portions of leaves are cut from said stems as the stems of said leaves are progressed between said members, said cutting members being disposed in close juxtaposition directly opposite to each other.

17. In a tobacco stemming machine, a leaf positioning table having downwardly inclined sides over which the laminae of leaves may be spread, means for directing a spreading blast 30 divergently against the upper surface of a leaf on said table, a plurality of spaced endless flexible stemming members provided with cutting edges, and means for driving said members whereby said edges cut the laminae from the 35 stems of leaves fed therebetween from said table.

18. In a stemming machine, the combination with means for feeding leaves to be stemmed, of a spreading table over which said leaves are 40 moved, a plurality of spaced pneumatic spreaders located above said table for directing a gaseous spreading medium under pressure over leaves positioned upon said table, and a plurality of spaced flexible stemming members adjacent 45 said table co-acting with said feeding means for stemming spread leaves fed therebetween, said stemming members being constructed and arranged to flex freely at their cutting edges to incline the said edges relatively to the broad faces 50 of the stemming members.

19. In a tobacco leaf stemming mechanism, a plurality of spaced stemming members, comprising rotary disks spaced from each other and mounted on inclined axes, a leaf support, and means for rotating said disks to impart cutting movement thereto, as the stems of leaves are fed therebetween for severing the laminae therefrom. 5

20. The combination with a pneumatic tobacco leaf positioning table, of means for drawing unstemmed leaves successively butt first, over said 10 pneumatic table, a pneumatic leaf spreading means positioned above said table for simultaneously directing a blast under pressure from the stem portion divergently toward either edge portion of the upper surface of a leaf drawn 15 over said table to spread said leaf, and mechanism for supplying gaseous fluid power for operating said table and means.

21. In a tobacco leaf spreading mechanism, a suction table for leaves to be spread, devices for 20 drawing unstemmed leaves successively butt first over said suction table while under the influence of suction applied through said table, a pneumatic leaf spreading means located above said table for simultaneously directing a blast of air 25 under pressure from the stem portion divergently toward either edge portion of the upper surface of a leaf being drawn over said table, said means being provided with a plurality of openings 30 through which said blast is ejected, and a source of supply of suction and compressed air for said table and means.

22. In a tobacco leaf spreading device, the combination with a leaf feeding and spreading table, of a pneumatic leaf spreading means 35 located above the table and from which air is ejected under pressure, said spreading means including baffles for directing air from said spreader against the stem portion of the leaf on said table divergently therefrom toward either 40 edge of the leaf to spread said leaf, and means for forcing air through said mechanism, said baffles having flat surfaces overlying and extending laterally to either side of the stem portion of a leaf fed over said table and acting to 45 confine the air under pressure close to the surface of the leaves while permitting the air to spread out laterally over the leaf.

GEORGE W. GWINN.

JAMES W. LEARY.
